UNITED STATES PATENT OFFICE.

EDWARD V. PHELPS, OF NASHUA, NEW HAMPSHIRE, ASSIGNOR TO IMPROVED PAPER MACHINERY COMPANY, OF NASHUA, NEW HAMPSHIRE, A CORPORATION OF MAINE.

FELT-COVERED SUCTION COUCH-CYLINDER.

1,241,272.

Specification of Letters Patent. Patented Sept. 25, 1917.

Application filed August 4, 1915. Serial No. 43,677.

To all whom it may concern:

Be it known that I, EDWARD V. PHELPS, a citizen of the United States, and a resident of Nashua, county of Hillsborough, 5 and State of New Hampshire, have invented an Improvement in Felt-Covered Suction Couch-Cylinders, of which the following description, in connection with the accompanying drawings, is a specification, like 10 characters on the drawings representing the parts.

This invention relates to improvements in rolls which, in certain aspects of the invention, may be used for various purposes 15 but which are particularly designed and adapted for use as couch rolls for paper making and pulp treating machinery.

In order that the principle of the invention may readily be understood, I have dis- 20 closed a single embodiment thereof in the accompanying drawing, wherein:

Figure 1 is a side elevation partially in section and with the central portion broken away of a couch roll embodying my in- 25 vention;

Fig. 2 is a longitudinal vertical central section thereof.

Fig. 3 is an end elevation thereof; and

Fig. 4 is a vertical transverse section 30 thereof.

These rolls are commonly formed from a rigid or semi-rigid core with an applied surface in the form of a relatively yielding and more or less frictional material. In 35 the construction of these rolls the surface is commonly applied by winding on the core a covering composed of one or more strips of suitable material, such, for example, as felt.

40 Referring more particularly to the drawings and to the single illustrative embodiment of the invention therein shown, I have therein represented the shaft 1 supported in suitable divided bearings 2-3 of any 45 suitable construction. Said bearings may be supported in any desired manner upon the frame or structure of the paper-making or pulp-feeding machinery, as, for example, upon beams 4, 5 not herein necessary more 50 fully to describe or disclose.

In the represented embodiment of my invention, to the specific details of form or relative arrangement of parts of which I am in no wise limited, except as claimed, I 55 have represented the shaft 1 as having fast

thereon spiders 6, 7 of which any desired number may be employed. In Fig. 4 I have represented the peripheral surfaces 8 of said spiders as polygonous in form thus forming salient angles 9. Said spiders may, how- 60 ever, be given any other suitable peripheral form.

The shell of the couch roll is herein shown as composed of a plurality of longitudinally extending lag-strips 10 which may be of any 65 suitable material but are preferably of wood. Each strip is supported flatwise upon alined flattened portions of the spiders and may be secured thereon in any suitable manner not herein necessary more fully to describe. 70 The roll is provided exteriorly of said annular series of lag-strips with a suitable covering of some preferably fibrous or soft spongy material such, for example, as felt. I have indicated such a covering at 11 in 75 Figs. 1 and 2. Said material may be of any suitable permeable nature. I have employed the word "permeable" in a broad sense as obviously the surface may be perforated or otherwise suitably formed or provided with 80 openings for the passage of the water or other liquid. The said covering for example may be of the character disclosed in Patent No. 1,173,736, granted to me Februa- 85 ry 29, 1916, wherein permeable material, ordinarily felt, in strip form is folded about a binding wire and with its edges directed outward and provided with transverse slits or scorings at intervals, is wound helically around the roll so as to form a permeable, 90 cylindrical surface by the succession of fabric edges tightly wound and compressed against each other upon the core.

I contemplate the provision of means for creating suction through the surface of the 95 couch roll. While this may be done in any suitable manner I preferably so form the lag-strips 10 as by inwardly beveling or tapering their lateral edges, as to provide suction chambers 12 between adjacent lag- 100 strips. Said suction chambers are herein represented as being triangular in cross-section and as extending substantially the entire length of the couch roll. I provide a suitable bottom for each of said suction 105 chambers 12 and herein for that purpose have represented sheet metal strips 13 of galvanized iron or other suitable material, the edges thereof being inserted in kerfs 14 formed in the lateral edges of the lag-strips 110

10. If desired, the strips 13 may be formed of wood or the lag-strips themselves may be so shaped as to provide bottomed suction chambers.

5 It will be noted that the outer edges of adjacent lag-strips 10 are slightly spaced apart, thus providing slits extending substantially the entire length of the couch roll and through which water or other liquid 10 may be drawn by suction through the felt covered roll. In order to afford additional opportunity for the admission of water or other liquid to the suction chambers 12, I may provide each of the lag-strips 10 or certain 15 of them, with suitably shaped passages 14' of any suitable length and extending through said lags from the outer surface thereof to the suction chambers. Said passages may extend substantially the entire 20 length of the lag-strips or be interrupted at suitable intervals so as not unduly to weaken said lag-strips.

At one or both ends of the couch roll and as herein indicated at both ends thereof, I 25 provide suitable ring or disk-like members, herein indicated at 15 and preferably formed of metal such, for example, as brass. The said disks or rings may be secured in any suitable manner to the end spiders 6, 7 as, 30 for example, by screws 16 so that they rotate with the couch roll to which a movement of rotation is imparted in any suitable manner not herein necessary more fully to describe.

Each of said disks or rings 15 is provided 35 with one or more openings or interruptions extending therethrough such, for example, as indicated at 17 whereby water or other liquid drawn by suction through the felt or other covering and through the suction 40 chambers of the roll, may be distributed in any suitable manner.

I contemplate the provision of preferably stationary means coöperating with said disks or rings 15 and through which the 45 water or other liquid may be drawn by suction and discharged. For this purpose I have herein represented hollow rings or annular chambers 18 herein shown as having open bases 19 which are in communication with the suction chambers 12. Preferably the plates 15 are provided with guiding annular flanges 21 for the reception of said rings or annular chambers. Thus, in the rotation of the couch roll the relative 50 positioning of the rotating portions of said roll with respect to the stationary rings or chambers 18, is preserved. The said rings or annular chambers 18 may be of any suitable material such, for example, as cast-iron 55 and each of them is provided with a suitable discharge opening indicated at 22 which may be threaded, if desired, for the reception of a preferably flexible pipe or hose connected to some suitable source of suction. If desired, any suitable coupling may

be provided between said pipe or hose and the rings or chambers 18.

Owing to the fact that a condition of relative rotation exists between the rings or annular chambers 18 and the couch roll 70 proper, I provide means to permit a slight relative yielding of said parts because of superficial irregularities or for other reasons. Inasmuch as in the disclosed embodiment of the invention the rings or annular 75 chambers 18 are stationary while the couch roll rotates, I have herein represented suitable yokes or frames 23 at opposite ends of the roll and herein shown as having annular portions at 24 encircling the bearings 2 and 80 3 of the roll. Said yokes may be secured in any suitable manner to the bearings 2, 3 or to the supporting beams 4, 5 thereof.

I provide each of the rings or annular chambers 18 with a plurality of guiding 85 pins 25 here shown as two in number and which extend through suitable openings 26 in the said yokes 23 thus permitting longitudinal movement of said pins through the yokes. Between the yokes 23 and the rings 90 or annular chambers 18, I provide any suitable yielding means, as, for example, coiled springs 27 which tend normally to hold the rings or annular chambers 18 in close relation to the rings or disks 15 but permit 95 slight yielding thereof owing to irregularities in the meeting surfaces or for other purposes.

My invention is not limited to the specific embodiment of means herein represented. 100 The suction chambers between the lags may be otherwise formed and it is not essential that lag-strips be employed as the roll may have any suitable surface which may be so modified as to form suitable suction chambers. 105 My invention may also be embodied in a roll not having a felt or like surface inasmuch as any surface material may be employed having provisions for permitting suction therethrough of water or other liquid 110 depending upon the use to which the roll is put. When there is employed, however, a form of covering similar to that shown in my prior patent aforesaid, because of the presence of the helical grooves in which the 115 binding wires are seated, and also the presence of the transverse slits, if the latter are employed, the suction is especially effective in withdrawing the water. The latter as it collects on the surface of the roll tends 120 quickly to diffuse throughout the felt and to come within the influence of the suction in one or more of the numerous and widely scattered suction passages 12 and 14'.

Assuming that the roll be used in the manufacture of paper or pulp, it will be understood from the foregoing description that the water or other liquid or a portion thereof is drawn by suction applied to the pipes or hose as described, in such manner as to 130

draw said water or liquid through the felt or like covered surface and into the suction chambers 12 and thence longitudinally thereof into the hollow rings or annular chambers 18.

Having thus described one illustrative embodiment of my invention, I desire it to be understood that although specific terms are employed they are used in a generic and descriptive sense and not for purposes of limitation, the scope of the invention being set forth in the following claims.

Claims.

1. A roll having a permeable surface, a supporting body therefor having longitudinally extending suction chambers, perforated rings at the ends of said roll, relatively stationary annular chambers mounted upon said ring, means for yieldingly supporting said annular chambers, and means for applying suction to said chambers.

2. A roll provided with a permeable surface 11, a lag-strip shell 10 providing chambers 12, and a relatively stationary annular chamber 18 in communication with said suction chambers 12.

3. A roll provided with a permeable surface 11, a lag-strip shell 10 providing chambers 12, a relatively stationary annular chamber 18 in communication with said suction chambers 12, and yielding supports 27 for said annular chamber 18.

4. A roll provided with a permeable surface comprising strip material wound spirally about said roll, a supporting shell therefor composed of lag strips spaced to provide longitudinal suction chambers, suction passages extending transversely through said lag strips and connecting said suction chambers with the under side of said permeable surface, and means for applying suction to said chambers.

5. A roll provided with a permeable surface comprising strip material wound spirally about said roll, a supporting shell therefor, suction passages arranged both longitudinally and transversely on said shell and communicating each with the under side of said permeable surface.

6. A roll provided with a permeable surface, a supporting body therefor having suction passages communicating with said permeable surface, said passages terminating in the end of the roll, a stationary suction chamber at the end of the roll and simultaneously communicating with all of said suction passages, and means for creating suction in said chamber.

7. A roll having a permeable surface, a

supporting body therefor, suction passages 60 for applying suction to said surface, said passages terminating in the end of the roll, a stationary annular suction chamber lying against the end of the roll and in sliding engagement therewith, and means for creating suction in said chamber whereby the same may be applied through said passages to said surface.

8. A roll having a permeable surface, journal bearings therefor, suction passages in 70 said roll communicating with said surface, a stationary suction chamber engaging the end of said roll and communicating simultaneously with all of said passages, means for yieldingly supporting said chamber, and 75 means for applying suction to said chamber.

9. A roll having a permeable surface, one or more suction passages communicating therewith, an end having a flat surface through which said passage or passages extend, a fixed suction chamber having a flat open face in sliding engagement with said end, and means for yieldingly pressing said suction chamber against said end to maintain communication between the same and 80 all of said suction passage or passages during rotation of said roll, and means for creating suction in said chamber.

10. A roll having a support, a permeable surface comprising strip material wound 90 spirally around said support, means for applying suction through said support to said permeable surface, and means for withdrawing the liquid.

11. A roll having a support, a permeable 95 surface having helical water conveying slits, and means for applying suction through said support to the under side of said permeable surface.

12. A roll having a support, a permeable 100 surface thereon secured by spirally arranged binding wires, said surface being transversely slit, and means for applying suction to the under side of said surface through said support.

13. A roll having a supporting shell composed of lag strips spaced to provide longitudinal suction chambers, a permeable surface for said roll comprising strips of permeable fabric wound thereon, and means for 110 applying suction to said chambers.

In testimony whereof, I have signed my name to this specification, in the presence of two subscribing witnesses.

EDWARD V. PHELPS.
